UNITED STATES PATENT OFFICE.

OTTO F. ERNST AND JOHN E. ERNST, OF SHERIDAN, WYOMING.

SADDLE.

Application filed July 23, 1928. Serial No. 294,799.

The present invention relates to improvements in harness and has reference more particularly to an improved riding saddle.

One of the important objects of the present invention is to provide a riding saddle wherein the old style front and back rigs, rings and front jockeys are eliminated thereby rendering the saddle less expensive in its manufacture and tending to prevent soreness of the animal's back such as is occasioned by the type of riding saddles now generally in use.

A further object is to provide a riding saddle wherein the stirrup straps are capable of forwardly and rearwardly swinging movement, this being especially advantageous to riders when riding bucking horses or in roping.

A further object is to provide a riding saddle which includes a reinforcement in the form of a curved metallic strip and takes the place of the conventional rings on the old type riding saddle.

Still a further object is to provide a riding saddle of the above mentioned character which is simple in construction, inexpensive, strong and durable and further well adapted to the purposes for which it is designed.

Other objects and advantages will become apparent during the course of the following description.

In the accompanying drawing, forming a part of this specification, and in which like numerals indicate like parts throughout the same:

Figure 1 is a perspective view of the riding saddle embodying our invention.

Figure 2 is an enlarged sectional view taken approximately on the line 2—2 of Figure 1.

In the drawing wherein for the purpose of illustration is shown the preferred embodiment of our invention, the numeral 1 designates generally our improved riding saddle, the same comprising a seat portion 2 and, arranged at the forward end thereof is the swell 3 from which extends upwardly the horn 4.

The usual cantle extending upwardly from the rear portion of the seat 2 opposite the pommel or swell 3 is denoted by the reference character 5. The skirt portion of the saddle is indicated at 6. The ridging associated with each side of the saddles includes the elongated tree fork 7 over which is looped the upper portion of the stirrup strap

8 the bottom of the stirrup strap may be so constructed as to constitute a stirrup 9 or may have a separate stirrup attached thereto as is desired.

Depending extensions 10 are formed at the sides of the seat portion 2 and as is clearly illustrated in Figure 1, each of these depending extensions is formed with an arcuate slot 11 to accommodate the outer and inner folds of the respective stirrup straps as well as the fender portion 12 associated with the stirrup strap.

The slot 11 is of such size as to permit the forward and rearward sliding movement of the stirrup straps on each side of the saddle and this construction is particularly advantageous to cowboys riding bucking horses or in roping.

The invention further comprehends the provision of an arcuate tapered metallic reinforcing strip 13 that is secured on the outer face of each extension 10 below the slot 11 as clearly suggested in the drawing and the purpose of the reinforcing element is to take the place of the usual metallic ring that heretofore connected the front and back rigs of an old type saddle, the front and back rigs being also eliminated together with the front jockeys.

The saddle is secured on the back of the horse by the usual cinch which passes underneath the body of the horse and the ends of the cinch are fastened to the saddle at each side by a strap commonly called a latigo which connects the end of the cinch to the rigging of the saddle.

A metal reinforcing strip 13 strengthens the portion of the saddle at the point where the latigo straps are attached to it.

It will thus be seen from the foregoing description, that we have provided a riding saddle that will not only be light in weight but will eliminate the use of a number of parts thereby rendering the saddle less expensive in its manufacture and sale.

Furthermore the rigging of our improved saddle will be strong and durable and will not be subjected to the same wear as the old type rigging used in conjunction with riding saddles now on the market.

While we have shown the preferred embodiment of our invention, it is to be understood that various changes in the size, shape and arrangement of parts may be resorted to without departing from the spirit of the invention and the scope of the appended claims.

Having thus described our invention, what we claim as new is:

1. In a riding saddle, a seat portion, extensions depending from the sides of said seat portion, a tree fork extending longitudinally beneath the seat portion at each side thereof, the depending extensions each being formed with an arcuate slot, and a stirrup strap pivoted at its upper end to the respective fork and 10 extending downwardly through the slot in the depending extensions.
2. In a riding saddle, a seat portion, extensions depending from the sides of the seat portion, each extension being formed with 15 an arcuate slot, a longitudinally extending tree fork arranged beneath the seat portion at each side thereof and above the respective slots, a stirrup strap connected at its upper end to each tree fork and extending downwardly through the arcuate slot in the adj- 20 acent depending extension as and for the purpose de- scribed.

cent depending extension for forward and rearward swinging movement.

3. In a riding saddle, a seat portion, extensions depending from the sides of the seat portion, each extension being formed with 25 an arcuate slot, a longitudinally extending tree fork arranged beneath the seat portion at each side thereof and above the respective slots, a stirrup strap connected at its upper end to each tree fork and extending down- 30 wardly through the arcuate slot in the adj- acent depending extension for forward and rearward swinging movement, and a metallic reinforcing strip secured to each depend- 35 ing extension as and for the purpose de- scribed.

In testimony whereof we affix our signatures.

OTTO F. ERNST.
JOHN E. ERNST.
